UNITED STATES PATENT OFFICE.

CHARLES O. WIDMAYER, OF OSWEGO, NEW YORK.

DESIGN FOR A SCARF-PIN.

SPECIFICATION forming part of Design No. 27,031, dated May 11, 1897.

Application filed January 9, 1897. Serial No. 618,653. Term of patent 7 years.

To all whom it may concern:

Be it known that I, CHARLES O. WIDMAYER, a citizen of the United States, residing at Oswego, in the county of Oswego and State of New York, have invented and produced a new and original Design for a Scarf-Pin, of which the following is a specification, reference being had to the accompanying drawings, showing a part thereof.

10 My invention consists in a scarf-pin or similar article. Its essential feature is a representation on a small scale of a velocipede or bicycle without its cranks or pedals and provided with the wheel-shaped disks of the peculiar configuration and appearance herein shown. It will be seen that these parts are not representations of the ordinary bicycle-wheels with fine spokes, but in place of the spokes have rather wide rings tapering from 15 the periphery to a central cylindrical panel and set at an angle, as shown.

The central panel is a suitable place for carrying the name of the maker or any other suitable words.

20 25 Referring to the accompanying drawings,

Figure 1 is a representation of my design for a scarf-pin, having the conventionalized shape of an ordinary safety-bicycle with the above exceptions; and Fig. 2 is a section through one of the wheels, illustrating more clearly 30 the tapering wings which I make use of instead of the ordinary spokes.

F designates the frame of the wheel.

W W are the wheels, having each a central panel P; S S, the spokes, which are tapering 35 and set oblique; N, a plate, which may be carried by the reach-bar of the frame, and D the driving-wheel.

What I claim as my design is—

The design for a scarf-pin, &c., substantially as herein shown and described.

In witness whereof I have hereunto set my hand, in the presence of two attesting witnesses, at Oswego, in the county of Oswego, in the State of New York, this 26th day of December, 1896.

CHARLES O. WIDMAYER.

Witnesses:

L. F. WEISBURG,
C. C. SCHONECK.
